MEDICAL EXAMINATION CABINET

Philmore W. Richmond, 1422 E. 18th Ave.,
Denver, Colo.

Filed May 24, 1965, Ser. No. 85,431

Term of patent 14 years

(Cl. D83—1)

FIG. 3.

FIG. 4.

FIG. 5.

The right-side elevation is a mirror-image of the left-side elevation and the bottom is plain except for the four legs at the corners.

I claim:

The ornamental design for a medical examination cabinet, as shown and described.
